ICED CAKE

Kenneth A. Patrick, Bethesda, Md.

Application February 5, 1954, Serial No. 28,872

Term of patent 14 years

(Cl. D82—2)

To all whom it may concern:

Be it known that I, Kenneth A. Patrick, a citizen of the United States, residing at Bethesda, in the county of Montgomery, State of Maryland, have invented a new, original, and ornamental Design for an Iced Cake, of which the following is a specification, reference being had to the accompanying drawing, forming a part thereof.

The single figure on the drawing is a side perspective view of an iced cake showing my new design.

Both sides of the iced cake are identical in appearance, the vertical rear portion is plain and unornamented and the upper portion is comparably rounded at the front and rear.

I claim:

The ornamental design for an iced cake, as shown and described.
